PRESSURE CONTROLLING APPLIANCE

Arthur Carter, Halesowen, near Birmingham,
and George Slade, Oldbury, England; said
Slade assignor to said Carter

Application July 6, 1949, Serial No. 103,272
In Great Britain July 8, 1948

1 Claim. (Cl. 267—1)

1

This invention relates to pressure controlling or cushioning appliances applicable to presses for the drawing or cupping of sheet-metal articles from blanks in order to give a controlled resisting pressure to the downward movement of the draw ring, but also being applicable generally for the purpose of offering a controlled resistance to a moving part; the said appliances being of the kind in which a hydraulic fluid is acted upon by a main ram or plunger in a primary cylinder and is forced through a resistance opening or passage into a secondary cylinder in order to act upon and depress a piston therein, said piston operating against a spring or other elastic medium which returns the piston and displaced fluid when the applied force is relieved from the ram or main plunger.

The object of the present invention is to provide an appliance of the kind referred to, with a self-contained resistance and return-flow unit that can be placed anywhere in a pipe line connecting the primary cylinder to the secondary cylinder, so as to be readily accessible for repairs or the like.

The accompanying drawing is a part sectional view of a pressure controlling appliance in accordance with the invention.

Referring to said drawing, which shows an appliance intended for cushioning the downward movement of the pressure or draw ring of a press, the usual pins depending from the said draw ring rest upon a pressure plate 1 supported upon the upper end of a main ram 3 movable vertically in a primary cylinder 4. This primary cylinder 4 is connected by pipes 33, 34, to a secondary cylinder 8 containing a vertically-moving piston 9 supported upon a spring 10 adapted to resist downward movement of the piston 9 and to return the same to its normal raised position. A pump is provided for automatically returning any fluid which has leaked past either the primary or secondary pistons. This pump comprises a hollow plunger 12 depending from piston 9 and sliding in a stationary cylinder 23. This cylinder has its upper portion of reduced diameter and the plunger 12 is grooved intermediate its ends, at 12¹. The said plunger has a single passage 27 in it, controlled by a ball valve 28 and passing from the lower face of the plunger 12 to the hollow interior, which is open to the top face of the piston 9. An inlet valve 30^a for the pump cylinder 23 is fitted to a passage 29^a in the bottom plate 45 closing the lower end of the cylinder. Any fluid leaking past piston 9 is received in the vessel 49 enclosing the pump, 55

2

whilst any liquid leaking upwards past the ram 3 can be discharged through pipe 51 into said vessel 49. When the plunger 12 rises, fluid from vessel 49 is drawn into cylinder 23 through valve 30^a and on the down stroke fluid is discharged through passage 27 until the plunger reaches a larger-diameter lower portion of cylinder 23.

The pipes 33, 34, are connected by a valve-controlled resistance unit. This unit comprises a body part or casting 35 having inlet and outlet branches 36, 37, respectively connected to the pipes 33, 34. The body 36 contains an upwardly-opening one-way valve 38 for the quick return of fluid from the cylinder 8 to cylinder 4, and this valve is by-passed by a passage 39 communicating with the space above said valve 38 by an opening 40 that is controlled by a spring-loaded valve 41 suitably guided in the wall of an extension part 42 of the body and having its end face subjected to the pressure of the fluid proceeding from the ram cylinder. The spring 43 acting on the valve, and normally causing it to close the said opening 40, is contained within the extension part 42 which is suitably attached to the body 35 and has screw means 44 for adjusting the strength of the spring. The valve 41 opens to an extent which is in accordance with the pressure of the fluid upon its end face, and thus automatically varies the resistance to the flow of the fluid so as to produce a substantially constant resistance to the movement of the ram.

The valve 38 can be raised from its seat and held in that position by means of a screwed rod 46 separate from said valve 38 but aligned with the stem thereof. A shut-off valve 47 is fitted in a pipe connection 48 between pipe 34 and a fluid-containing vessel 49 on which the cylinder 8 is mounted, whilst a non-return valve is fitted at 50 in the pipe 51 between the upper end of cylinder 4 and the said pipe connection 48. With this arrangement, by raising valve 38 and opening shut-off valve 47 the weight of the pressure plate 1 and ram 3 in the primary cylinder 4 is sufficient to discharge the fluid from said cylinder 4 into the vessel 49. This is necessary in order that tools may be set on large presses. The non-return valve at 50 prevents fluid from passing back into the cylinder 4 and above the ram 3 during this operation, but any fluid leaking upwards past the ram 3 can be discharged through pipe 51 into the vessel 49.

Also, by very slightly raising the valve 38 with the stop valve 47 shut, lower pressures than are normally required for making pressings can be obtained, as according to the distance the valve

38 is raised, so more or less fluid is by-passed around the resistance valve 41 without having to pass through the restricted aperture 40.

We claim:

A hydraulic pressure-controlling appliance comprising a primary cylinder containing a hydraulic fluid, a pressure-applying ram in said cylinder, a secondary cylinder connected to the primary cylinder by a pipe line, a piston in the secondary cylinder, elastic means resisting movement of the piston, and a combined resistance-valve and quick-return valve unit in the pipe line, said unit consisting of a body having an inlet branch and an outlet branch and forward-flow and return-flow passages between said branches, a spring-loaded resistance valve in said body controlling the flow of fluid from the primary to the secondary cylinder through the forward-flow passage in the body, being subjected to the fluid pressure prevailing in the primary cylinder and operating to restrict said flow to an extent that varies inversely with the said fluid pressure, a one-way valve controlling the return-flow passage in the body and which opens only to

permit the return flow of fluid from the secondary cylinder to the primary cylinder, and an externally-operable axially movable rod for raising the one-way valve from its closed position and for holding it in such raised position.

ARTHUR CARTER,
GEORGE SLADE.
